No. 867,095.

PATENTED SEPT. 24, 1907.

T. A. BEMUS.
CIRCUIT CLOSER.
APPLICATION FILED MAR. 2, 1905.

UNITED STATES PATENT OFFICE.

THOMAS ALTON BEMUS, OF BOSTON, MASSACHUSETTS, ASSIGNOR TO T. ALTON BEMUS COMPANY, INCORPORATED, OF BOSTON, MASSACHUSETTS, A CORPORATION OF MASSACHUSETTS.

CIRCUIT-CLOSER.

No. 667,995.

Specification of Letters Patent.

Patented Sept. 24, 1907.

Application filed March 2, 1905. Serial No. 248,153.

To all whom it may concern:

Be it known that I, THOMAS ALTON BEMUS, of Boston, in the county of Suffolk and State of Massachusetts, have invented certain new and useful Improvements in Circuit-Closers; and I do hereby declare the following to be a full, clear, and exact description of the invention, such as will enable others skilled in the art to which it appertains to make and use the same.

The primary object of this invention is to provide a circuit closer, especially adapted for multiple explosion engines, wherein the wires will be secured to a part which may be readily removed from the shaft carrying the complementary part or brush. And further objects are to so construct the brush as to insure the engagement thereof with the contact plates and guard against breakage or undue wear; and also to enable the complementary parts to be relatively shifted so as to advance or postpone the time of closing the circuit according to the speed at which it is desired the engine should run.

The invention will be hereinafter fully set forth and particularly pointed out in the claims.

In the accompanying drawings, Figure 1 is a view in perspective. Fig. 2 is a vertical sectional view. Figs. 3 and 4 are face views of the two parts constituting the enclosure or casing.

Referring to the drawings, 1 designates the rotary shaft upon which the circuit closer is located, such shaft being preferably that by which the valves of a gas engine are operated.

2 designates an inclosing casing preferably constructed throughout of insulating material, with the exception that its cover plate 3 is preferably made of metal. The casing comprises a cap having an outer right wall 4 and a circumferential wall 5, in which latter are set contact plates 6 carrying binding posts 7 to which the several wires of a multiple gas engine may be secured. These contact plates are preferably countersunk in the inner surface of the circumferential wall, so as to be flush therewith. The cover plate 3 is preferably secured to the cap by nutted screws 8, and is provided with an extension 9 to which a rod or wire 10 may be secured for shifting the positions of the casing and the contact plates. The plate 3 is formed with a central outwardly extending boss fitted with a bushing 12, and into this bushing is extended a bearing sleeve 13 having at one end a flange 14 conforming to the boss at the hub of plate 3. This flange may form part of a bracket secured to some permanent support, such as the under side of a motor vehicle, such bracket being indicated in dotted lines at 15, Fig. 1. The shaft 1 passes through this sleeve, and is free to rotate

therein, while the plate 3 of the casing is free to rotate on said sleeve.

16 designates the contact brush which is secured fast on shaft 1 at right angles thereto and designed to rotate within the inclosing casing 2 and effect contact with the several contact plates 6. This brush comprises a ball 17 in the outer end of a sleeve 18 telescoping an inner larger sleeve 19, which latter is secured to a ring 20, preferably by being screwed onto a threaded boss extending from the periphery of such ring, a spring 21 being located within the telescoping sleeves so as to hold the sleeve 18 and ball 17 in their outwardly projected positions, and yet allow of their being forced inwardly as far as the outer end of the immovable sleeve 19. The ring 20 is keyed to the end of shaft 1, preferably by a screw 22 screwed into the end of said shaft, a retaining screw 23 preventing any displacement of the locking screw.

From what has been said it will be seen that as the shaft 1 rotates the ball 17 of the brush will travel around the circumferential wall of the inclosing cap, in either direction, and engage with each of the several contact plates 6, and by reason of the spring pressure a firm and positive contact is had in each instance. But even aside from the pressure of the spring the centrifugal action insures the engagement of the ball contact with the plates 6. Furthermore, the brush as thus constructed is extremely strong and durable and will allow of a great amount of usage owing to its self adjustment, the inclosing spring tending to always hold the movable parts of the brush in their outermost positions.

In practice, when it is desired to advance or retard the time of closing the circuits, as when it is desired to increase or decrease the speed of an engine, it is only necessary to shift the inclosing casing on its independent bearing afforded by the sleeve 13. I have found it of decided advantage to provide this independent bearing for the contact carrying casing in that it permits of the shifting of the latter free from any counter-acting influences of the rotary shaft. Furthermore, when it is desired to gain access to the brush it is only necessary to remove the nuts of screws 8 and withdraw the cap to which the several wires are secured. In this way all entanglement or danger of breaking or otherwise interfering with the wires is avoided, since they may remain permanently fastened to the removed cap. This latter, it will be noted, is beyond the end of the shaft, only the cover plate 3 being mounted on such shaft.

A circuit closer constructed as herein described is extremely simple and inexpensive and not liable to read-

ily get out of order. One particular advantage is that an extended or increased bearing is provided by the sleeve 13 extended through the hub of the cover plate of the casing, thus preventing wabbling or displacement of the device when mounted on the shaft.

5 I claim as my invention:—

1. The combination with a rotary shaft, the casing having a circumferential wall, contacts in the inner face of said wall, of a brush fixed to said shaft comprising two 10 telescoping sleeves, and a ball at the outer end of one of said sleeves, the other sleeve being fixedly mounted, and a spring inclosed by said sleeves, as set forth.

2. The combination with a rotary shaft, the casing having a circumferential wall, and a series of contact plates in the inner face of said wall, of a brush fixed to said shaft 15 comprising a ring having a threaded boss, two telescoping sleeves, one being secured to said boss, a ball in the outer end of the other sleeve, and a spring for holding such latter sleeve and ball in their extended positions.

In testimony whereof, I have signed this specification in 20 the presence of two subscribing witnesses.

THOMAS ALTON BEMUS.
